UNITED STATES PATENT OFFICE.

FRANK P. DUNN, OF ANDERSON, INDIANA, ASSIGNOR TO COMPUTING CHEESE CUTTER COMPANY, OF ANDERSON, INDIANA, A CORPORATION OF INDIANA.

CHEESE-CUTTER.

1,139,405.

Specification of Letters Patent.

Patented May 11, 1915.

Application filed September 16, 1912. Serial No. 720,447.

To all whom it may concern:

Be it known that I, FRANK P. DUNN, a citizen of the United States, residing at Anderson, in the county of Madison and State of Indiana, have invented a new and useful Cheese-Cutter, of which the following is a specification.

The object of my invention is to produce an efficient mechanism for accurately gaging the amount of possible movement of the cheese-carrying table of a cheese cutter by means of which accurately proportioned portions may be cut and dispensed.

The accompanying drawings illustrate my invention.

Figure 1 is a perspective view of the complete apparatus; Fig. 2 a plan in partial horizontal section showing my improved table-driving mechanism; Fig. 3 a fragmentary plan on a larger scale of the table-driving mechanism; Fig. 4 an under plan of the parts shown in Fig. 3; Fig. 5 an elevation, in partial vertical section, of the parts shown in Fig. 3, with a fragment of the table casting in vertical section; Fig. 6 an elevation of my improved gage.

In the drawings, 10 indicates a main base casting upon which is hinged, at 11, the common cutting knife 12. The base casting 10 is provided with a diametrical cross bar 13 in the center of which is pivoted a table-carrying casting 14 of substantially circular form and provided with a depending annular flange 15. The casting 14 is adapted to receive and carry a usual cheese-carrying table 16. The casting 14 is provided with a pivot pin 17 and journaled upon this pin is an operating arm 18 which is projected through an opening in the base casting and formed at its outer end to serve as an operating handle. The upper surface of the lever 18 is conveniently formed with a depression or pocket 19 in which I mount my improved clutch plate 21. This clutch plate 45 at its inner end is provided with a pair of substantially parallel fingers 22, 22 which straddle the shank of a screw 23 mounted in the bottom of pocket 19, the fingers 22 passing snugly beneath the head of the screw 23. The upper face of the clutch plate 21 is provided with two vertical pins 24 and 25 which are substantially parallel and are arranged to lie upon opposite sides of the flange 15 and are displaced angularly

with relation to said depending flange, as 55 clearly shown in Fig. 3. The pin 25 is projected through the plate 21 and through opening 26 formed through lever 18 and engaging the lower end of the pin 25 is a spring 27 which serves to normally swing 60 the clutch plate upon pin 23 as a pivot so as to hold the two pins 24 and 25 in engagement with the depending flange 15. By this arrangement it is not essential that the flange 15 be absolutely concentric with the 65 pin 17 because the clutch plate 21, by reason of the fingers 22 and screw 23, is free to slide longitudinally of the lever 18, as well as to swing upon pin 23 as a pivot. The table 16 may be advanced step by step in 70 one direction by reciprocation of lever 18.

It has heretofore been common to provide cheese-carrying tables of this type with friction ratchet mechanism by means of which they can be advanced, but difficulty 75 has been experienced in definitely controlling the amount of movement of the table because of the tendency of the table, when once set in motion, to continue after the operating lever is brought to a stop. In order 80 to avoid this difficulty, I provide the plate 21 on its forward side with a finger portion 28 which comes against a portion 29 of the base 10 in order to limit the forward movement of the lever 18, this limitation of the 85 forward movement of the lever thus simultaneously serving to insure a proper grip of the pins 24 and 25 upon the flange 15 and thus prevent any "throwing by" of the table. It will therefore be seen that, no 90 matter with what force the lever 18 be shifted, there can be no advancement of the table after the lever has come to a stop.

It is necessary that the forward advancement of the table 16 be accurately gaged in 95 order that the store keeper may accurately deliver to the customer a desired amount of cheese (either by weight or value) and for that purpose I provide the base 10 with a projection 31 adjacent the point where lever 100 18 emerges through the wall of the base. This projection is then bored with a straight bore 32 (dotted lines Fig. 2) through which a threaded gage 33 may pass. Projected transversely into the bore 32 is a guide and 105 clamping pin 34 which is threaded in the wall of the bore so that its inner end may not only serve as a guide, to prevent longi-

tudinal movement of the gage pin 33 except by rotation, but also serves as a clamping screw to hold the screw at any desired position of adjustment. Screw 33 is preferably provided with a square thread, as shown, in order that the threads may present a sufficient surface upon which to receive legible gage markings 35 to coöperate with the gage mark 35' arranged on the face of a notch 36 10 cut in the upper surface of projection 31. Threaded into the inner end of the gage screw 33 is a temper screw 37 which serves as a stop for the reverse movement of lever 18, the arrangement being such that, by adjustment of the temper screw 27, accuracy of the position of the gage screw with relation to the lever 18 may be attained without especial care in the placing of the clamping screw 34 which determines the axial position of the gage screw 33.

20 The gage markings 35 may be designated and arranged in any desired manner. If it is the desire of the operator to first figure the total retail value of an entire cheese and then dispense the same in five-cent pieces, or pieces having a value in multiples of five cents, the gage markings 35 will be "total value" markings as indicated in Fig. 6. If, on the other hand, the operator desires to dispense the cheese by weight units, the markings 35 will be indicated by the total weight indications and be correspondingly arranged with relation to each other along the length of the screw thread.

35 By the above construction, it will be noticed that the apparatus may be assembled after a very small amount of simple machine work, which can be readily done by comparatively unskilled labor, thus making it possible to produce an accurate cheese cutter at small expense.

I claim as my invention:

1. In a cheese cutter, the combination of a base, a cheese-carrying table rotatably mounted thereon, an operating lever, a clutch between said lever and table, means for limiting the movement of said lever in one direction, and a means for limiting the movement of said lever in the opposite direction comprising a threaded gage member carrying gage markings arranged longitudinally of the thread thereof, and means for preventing axial movement of said gage member except upon rotation.

55 2. In a cheese cutter, the combination of a cheese-carrying table, a supporting base member having a lateral extension bored transversely of the axis of the table, a threaded gage member journaled in said bore and provided at its inner end with an axial temper screw, a clamping and retaining screw projected into said bore in position to lie between the threads of the gage screw, an operating lever arranged to engage said temper screw at one end of its movement,

clutching means arranged between the operating lever and table, and means for limiting the throw of said lever in the opposite direction.

3. In a cheese cutter, the combination of a cheese-carrying table, a supporting base member having a lateral extension bored transversely of the axis of the table, a threaded gage member journaled in said bore, a clamping and retaining screw projected into said bore in position to lie between the threads of the gage screw, an operating lever arranged to engage said gage screw at one end of its movement, clutching means arranged between the operating lever and table, and means for limiting the throw of said lever in the opposite direction.

4. In a cheese cutter, the combination of a cheese-carrying table, a supporting base member having a lateral extension bored transversely of the axis of the table, a threaded gage member journaled in said bore, a clamping and retaining screw projected into said bore in position to lie between the threads of the gage screw, an operating lever arranged to engage said gage screw at one end of its movement, clutching means arranged between the operating lever and table, and means engaging the clutching means to limit the throw of the lever in the forward direction and to simultaneously tighten the clutching means.

5. In a cheese cutter, the combination of a rotary table, having an annular flange, an operating lever swinging in a plane substantially parallel with the table, a clutch plate mounted on said lever and freely movable angularly and radially thereon, clutch pins carried by said clutch plate and engaging the annular flange upon its opposite sides, and a stop arranged in the path of movement of said lever in one direction to engage said clutch plate so as to limit the movement of the lever and simultaneously tighten the clutch pins upon the flange.

6. In a cheese cutter, the combination of a rotary table, having an annular flange, an operating lever swinging in a plane substantially parallel with the table, a clutch plate mounted on said lever and freely movable angularly thereon, clutch pins carried by said clutch plate and engaging the annular flange upon its opposite sides, and a stop arranged in the path of movement of said lever in one direction to engage said clutch plate so as to limit the movement of the lever and simultaneously tighten the clutch pins upon the flange.

7. In a cheese cutter, the combination of a rotary table, an operating lever swinging in a plane substantially parallel with the table, clutching means carried by said lever and engaging the table, and a stop arranged in the path of movement of said clutching means to engage said clutching means so as

to limit the swinging of the operating lever in one direction and simultaneously tighten the clutching means upon the table.

8. In a cheese cutter, the combination of a rotary table, a reciprocating operating member, a clutch connection between said operating member and table to drive the table in one direction, and means causing said clutch connection to automatically firmly grip the table and hold the same against further forward advancement when the operating member reaches its normal limit of forward movement.

9. In a cheese cutter, the combination of a rotary table, an operating member, a clutch connection between said operating member and table, and means for engaging said clutch connection and tightening the same upon the table to prevent further forward advancement of the table when the operating member reaches its normal limit of forward movement.

10. In a cheese cutter, the combination of a cheese carrying member and a knife one movable relatively to the other transversely to the knife, an operating member for advancing the movable member, a clutch connection between the operating member and movable member, and means causing said clutch connection to automatically firmly grip the movable member and hold the same against further advancement when the operating member reaches its normal limit of forward movement.

11. In a cheese cutter, the combination of a cheese carrying member and a knife one movable relatively to the other transversely to the knife, an operating member for advancing the movable member, a clutch connection between the operating member and movable member, and means for engaging said clutch connection and tightening the same upon the movable member to prevent further forward advancement of said movable member when the operating member reaches its normal limit of forward movement.

12. In a cheese cutter, the combination of a main frame, a cheese carrying table rotatably mounted on the main frame, a driving member movable in a single plane, means carried by said driving member and engaging the table to advance the same step by step, and a limiting stop rotatably mounted upon the main frame in the plane of movement of the driving member and rotatable to different positions to variably limit the movement of the driving member in one direction.

13. In a cheese cutter, the combination of a main frame, a cheese carrying table rotatably mounted on the main frame, a driving member movable in a single plane, means carried by said driving member and engaging the table to advance the same step by

step, and a limiting stop rotatably mounted upon the main frame in the plane of movement of the driving member and rotatable to different positions to variably limit the movement of the driving member in one direction, and a graduated scale and coöperating indicator, one carried by the frame and the other by the rotatable stop to indicate the limiting position of the rotatable stop relative to the actuated member.

14. In a cheese cutter, the combination of a main frame, a cheese carrying table rotatably mounted on said main frame, a driving member movable in a single plane, means carried by said driving member and engaging the table to advance said table step by step, a fixed stop carried by the main frame to limit the movement of the driving member in one direction, and an adjustable stop rotatably mounted upon the main frame in opposition to the fixed stop and rotatable to vary the space between itself and the fixed stop to vary and limit the movement of the driving member in the opposite direction.

15. In a cheese cutter, the combination with the main frame, of a cheese carrying table movably mounted on the main frame, a driving member, a clutch carried by the driving member and engaging the cheese table to advance the same in one direction step by step, a fixed stop carried by the main frame and arranged in the path of table-advancing movement of the clutch to tighten the clutch against the table and thereby limit the advancing movement of the table, and an adjustable stop rotatably mounted upon the main frame in opposition to the fixed stop and in position to limit the return movement of the driving member, whereby the adjustable stop may be shifted to vary the distance between itself and the fixed stop.

16. In a cheese cutter, the combination with the main frame, of a cheese carrying table movably mounted on the main frame, a driving member, a clutch carried by the driving member and engaging the cheese table to advance the same in one direction step by step, a fixed stop carried by the main frame and arranged in the path of table-advancing movement of the clutch to tighten the clutch against the table and thereby limit the advancing movement of the table, and an adjustable stop mounted upon the main frame in opposition to the fixed stop and in position to limit the return movement of the driving member, whereby the adjustable stop may be shifted to vary the distance between itself and the fixed stop.

17. In a cheese cutter, the combination of a main frame, a cheese carrying table movably mounted on the main frame, a driving member movable in a single plane, means carried by said driving member and engaging the table to advance the same step by

step in one direction, and a limiting stop rotatably mounted upon the main frame in the plane of movement of the driving member and rotatable to different positions to variably limit the movement of the driving member in one direction.

In witness whereof, I have hereunto set

my hand and seal at Anderson, Indiana, this 29th day of August, A. D. one thousand nine hundred and twelve.

FRANK P. DUNN. [L. S.]
